UNITED STATES PATENT OFFICE.

BENJAMIN F. ROBERTS AND WILLIAM AUTBURN ROBERTS, OF BRAZIL, INDIANA.

GAS-GENERATOR.

1,237,557.

Specification of Letters Patent. Patented Aug. 21, 1917.

Application filed December 28, 1916. Serial No. 139,355.

To all whom it may concern:

Be it known that we, BENJAMIN F. ROBERTS and WILLIAM A. ROBERTS, citizens of the United States, residing at Brazil, in the 5 county of Clay and State of Indiana, have invented certain new and useful Improvements in Gas-Generators, of which the following is a specification, reference being had to the accompanying drawings.

10 This invention comprehends certain new and useful improvements in acetylene gas generators, and relates particularly to an improved device of this character which is designed for use in recharging gas tanks 15 such as those used with automobiles, motorcycles and the like for illuminating purposes.

The invention has for its primary object a practical, durable and efficient construction of device of this character, the parts of which may be easily manufactured and assembled and not liable to get out of order, and such as to require very little if any, attention in operation, and the invention also 25 aims to generally improve devices of this class so as to render them more useful and commercially desirable.

With these and other objects in view, as will more fully appear as the description 30 proceeds, the invention consists in certain constructions, arrangements and combinations of the parts that we shall hereinafter more fully describe and claim.

For a full understanding of the invention, 35 reference is to be had to the following description and accompanying drawing, in which—

Figure 1 is a vertical longitudinal sectional view of an acetylene gas generator 40 embodying the improvements of our invention,

Fig. 2 is a side elevation of the apparatus, and

Fig. 3 is a horizontal section on the line 45 3—3 of Fig. 1.

Corresponding and like parts are referred to in the following description and designated in all of the views of the accompanying drawing by like reference characters.

50 Our improved gas generating device comprises superposed cylinders 1 and 2 that are provided at their abutting ends with flanges 3 whereby they may be readily secured together in a detachable manner by bolts or 55 similar fastening devices 4. Preferably the

upper cylinder 1 has legs 5 secured to it whereby the device may be readily supported upon the ground or floor.

The upper cylinder 1 is provided with a bottom 6 having openings 7 and 8 extending therethrough, the opening 7 being preferably threaded and designed to receive the lower threaded end of a vertically disposed tube 9 which extends upwardly within the cylinder 1 above the level of the water which 60 said cylinder is intended to contain. The opening 8 constitutes a seat for a valve 10 carried by and secured to the lower end of a vertically disposed stem 11 which extends upwardly in and above the upper end of the 70 cylinder 1 and through a head or cap disk 12 secured by bolts or similar fastening devices 13 to the upper flange 14 of said cylinder, and the upper end of the stem 11 is provided with a finger piece 15 by which it may 75 be easily manipulated. Preferably, the head or cap disk 12 carries a pressure gage 16 and a safety valve 17 as shown.

The upper cylinder 1 is formed with a lateral enlargement which is vertically elongated, as shown, and which constitutes a chamber 18, said chamber being closed at its bottom as clearly illustrated in the drawing, and provided at its bottom with a laterally disposed port 19 which communicates with 80 the lower end of a vertical passage 20 formed by a wall or partition 21 as shown, and leading at its upper end by means of a lateral port 22 into the interior of the cylinder 1 near the upper end of the latter and 85 preferably substantially in horizontal alignment with the upper end of the tube 9. The chamber 18 contains a filter 23 of gauze or the like, supported upon lugs 23' or similar devices; and above the filter the chamber is 90 provided with an outlet 25 through which the gas issues, and from which it is designed to pass into the tank to be filled.

95 Preferably a wire basket 26 is disposed within the lower cylinder 2, for the purpose 100 of holding the carbid, and said cylinder is provided with a drain cock 27.

From the foregoing description in connection with the accompanying drawing, the 105 operation of our improved acetylene gas generator for refilling gas tanks will be apparent. In the practical use of the device, water is contained within the cylinder 1 and the chamber 18 and carbid is held within the basket 26 in the lower chamber 2, 110

said lower chamber being connected by the bolts 4 to the upper chamber after the lower chamber is filled. Upon opening the valve 10 by manipulating the valve stem 11, it is 5 obvious that the water falling from the upper cylinder 1 into the lower cylinder 2 will cause the gas to be generated, and the gas will flow upwardly from the cylinder 2 through the tube 9 and then downwardly through the passage 20 into the water contained within the chamber 18 and finally upwardly through the preferably 10 gauze filter 23 from whence it will be passed into the tank to be filled or refilled, so that 15 the gas will be thoroughly filtered and cleansed of all dust and other impurities.

While the accompanying drawing illustrates what we believe to be the preferred embodiment of our invention, it is to be 20 understood that the invention is not limited thereto, but that various changes may be made in the construction, arrangement, and proportions of the various parts without departing from the scope of the invention as 25 claimed.

What is claimed, is:—

1. A gas generator of the character described, comprising upper and lower cylinders connected together in superposed relation, legs connected to the upper cylinder and supporting same with the lower cylinder suspended therefrom, the upper cylinder being provided with a lateral enlargement constituting a vertically elongated chamber, and 30 said chamber and the upper cylinder being designed to contain water, and the lower cylinder to contain carbid, the upper cylinder being provided with a bottom having openings extending therethrough, a valve controlling one of said openings and provided 35 with a stem extending upwardly above the top of the upper cylinder, a tube mounted in the upper cylinder with its lower end in the other opening, and a filter in the upper end 40 of said chamber, there being upper and lower ports and a vertically disposed passage establishing communication between the upper end of the upper cylinder on a line 45 with the upper end of said tube, and the

lower end of said chamber, substantially as 50 shown and described.

2. A gas generator of the character described, comprising upper and lower cylinders arranged in superposed relation to each other, the lower cylinder being designed to 55 contain carbid and the upper cylinder water, a tube mounted in the upper cylinder and vertically disposed therein and communicating with the interior of both cylinders, and a valve designed to establish communication 60 between said cylinders independently of said tube, the upper cylinder being formed with a vertically elongated enlargement, with a vertically disposed passage and upper and lower ports establishing communication, respectively, with the upper end of said cylinder and the lower end of said chamber, and 65 said chamber being provided at its upper end with an outlet opening.

3. A gas generator of the character described, comprising upper and lower cylinders arranged in superposed relation to each other, the lower cylinder being designed to 70 contain carbid and the upper cylinder water, a tube mounted in the upper cylinder and vertically disposed therein and communicating with the interior of both cylinders, and a valve designed to establish communication 75 between said cylinders independently of said tube, the upper cylinder being formed with a vertically elongated enlargement, and a vertically disposed passage and upper and lower ports establishing communication, respectively, between the upper end of said cylinder and the lower end of said chamber, 80 and said chamber being provided at its upper end with an outlet opening, said chamber being also formed with lugs below said opening, and a filter supported on said lugs.

In testimony whereof we hereunto affix 90 our signatures in the presence of two witnesses.

BENJAMIN F. ROBERTS.

WILLIAM AUTBURN ROBERTS.
